(57) **CLAIM**

The ornamental design for a wheel for motor vehicle as shown and described.

DESCRIPTION

FIG. 1 is a perspective view of a wheel for motor vehicle according to a first embodiment showing my new design; FIG. 2 is a left view thereof shown slightly rotated; FIG. 3 is a right view thereof shown slightly rotated; FIG. 4 is a rear view thereof shown slightly rotated; FIG. 5 is a front view thereof shown slightly rotated; FIG. 6 is a top view thereof shown slightly rotated; and FIG. 7 is a bottom view thereof shown slightly rotated. FIG. 8 is a perspective view of a wheel for motor vehicle according to a second embodiment showing my new design; FIG. 9 is a left view thereof shown slightly rotated; FIG. 10 is a right view thereof shown slightly rotated; FIG. 11 is a rear view thereof shown slightly rotated; FIG. 12 is a front view thereof shown slightly rotated; FIG. 13 is a top view thereof shown slightly rotated; and FIG. 14 is a bottom view thereof shown slightly rotated. The portions of the wheel for motor vehicle shown in broken lines are for illustrative and environmental purposes and form no part of the claimed design.
